DISPLAY PACKAGE

James Clancy, Garden City, N. Y.

Application April 8, 1954, Serial No. 29,908

Term of patent 14 years

(Cl. D80—5)

To all whom it may concern:

Be it known that I, James Clancy, a citizen of the United States, residing at Garden City, county of Nassau, State of New York, have invented a new, original, and ornamental Design for Display Package, of which the following is a specification, reference being had to the accompanying drawing, forming part thereof, wherein—

Figure 1 is a front perspective view of a display package embodying my design;

Figure 2 is a side elevational view of the display package; and

Figure 3 is a rear elevational view of the display package.

The dominant features of my design reside in the portions shown in full lines.

I claim:

The ornamental design for a display package, as shown and described.
